CLAIM

The ornamental design for a container for packaging product, as shown and described.

DESCRIPTION

FIG. 1 is a perspective view of a container for packaging product showing our new design;

FIG. 2 is a front elevational view thereof;

FIG. 3 is a right side elevational view thereof;

FIG. 4 is a top plan view thereof;

FIG. 5 is a rear elevational view thereof;

FIG. 6 the left side elevational view thereof; and,

FIG. 7 is a bottom plan view thereof.

The broken lines shown in the drawings depict environmental subject matter and form no part of the claimed design.
